DASCENZO GATES LLC**CLAIM**

The ornamental design for a slider top for hydration reservoir, as shown and described.

DESCRIPTION

FIG. 1 is a top front isometric view of the new design;
FIG. 2 is a bottom rear isometric view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.
